United States Patent Office

Des. 182,460
Patented Apr. 8, 1958

182,460

PROJECTOR

Harold G. Fitz Gerald, Los Angeles, Calif.

Application March 29, 1957, Serial No. 45,492

Term of patent 14 years

(Cl. D61—1)

Fig. 1.

Fig. 2.

Fig. 3.

Fig. 4.

Fig. 1 is a side elevational view of a projector, showing my new design;

Fig. 2 is a front elevational view;

Fig. 3 is a rear elevational view; and,

Fig. 4 is a top plan view thereof.

A portion of the drawing figures is diagonally lined to indicate transparency.

I claim:

The ornamental design for a projector, as shown and described.
